US00D813399S

(12) **United States Design Patent** (10) Patent No.: **US D813,399 S**
(45) Date of Patent: **** Mar. 20, 2018**

(54) **HEAD POSITIONER**

(71) Applicant: **Ansell Limited**, Richmond, Victoria (AU)
(72) Inventors: **Jennifer Barber**, Simi Valley, CA (US); **Adam Weintraub**, Calabasas, CA (US); **Noel Muldowney**, County Kildare (IE); **Michael Lawler**, County Kildare (IE)

(73) Assignee: **Ansell Limited**, Victoria (AU)

(**) Term: **15 Years**

(21) Appl. No.: **29/597,890**

(22) Filed: **Mar. 21, 2017**

(51) LOC (11) Cl. **24-01**

(52) U.S. Cl.

USPC **D24/184**

CLAIM

The ornamental design for a head positioner, as shown and described.

DESCRIPTION

FIG. 1 is a perspective view of a head positioner showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

1 Claim, 6 Drawing Sheets
